CLASP

Raymond W. Cook, Bristol, Conn., assignor, by
mesne assignments, to Associated Spring Cor-
poration of Delaware, Bristol, Conn., a corpo-
ration of Delaware

Application February 7, 1935, Serial No. 5,413

5 Claims. (Cl. 24—243)

This invention relates to improvements in clasps, and more particularly to clasps for use on personal wear such, for example, as garters.

One object of this invention is to provide an improved clasp, capable of being clasped and unclasped with maximum speed and minimum ease.

Another object of this invention is to provide an improved clasp which will not tear the fabric to be held.

Another object of this invention is to provide an improved clasp of maximum thinness.

Another object of this invention is to provide an improved clasp formed of simple elements readily manufactured and readily assembled to produce an attractive, durable, efficient construction at minimum cost.

With the above and other objects in view, this invention includes all improvements over the prior art which are disclosed in this application.

In the accompanying drawings, in which certain ways of carrying out the invention are shown for illustrative purposes:

Fig. 1 is a front elevation of a garter having a clasp thereon made in accordance with this invention;

Fig. 2 is an enlarged vertical sectional view on the line 2—2 of Fig. 1;

Fig. 3 is a perspective view of the clasp shown in Figs. 1 and 2;

Fig. 4 is a view similar to Fig. 2, of a modified form of clasp;

Fig. 5 is a front elevation of another modified form of clasp made in accordance with this invention;

Fig. 6 is a sectional view on the line 6—6 of Fig. 5;

Fig. 7 is a sectional view on the line 7—7 of Fig. 5;

Fig. 8 is a front elevation of the frame-member shown in Fig. 5;

Fig. 9 is a front elevation of another modified form of clasp made in accordance with this invention;

Fig. 10 is an enlarged sectional view on the line 10—10 of Fig. 9;

Fig. 11 is a perspective view of the clasp shown in Fig. 9;

Fig. 12 is a front elevation of the resilient clasp-member shown in Fig. 9; and

Fig. 13 is a front elevation of another modification of a clasp made in accordance with this invention.

In the description and claims, the various parts are identified by specific names for convenience,

but they are intended to be as generic in their application as the prior art will permit.

Referring to Figs. 1 to 3 of the drawings, the clasp 20 includes a frame-member 21 having a crossbar 22 at its upper end, about which is secured a depending-portion 23 of a garter 24. The frame-member 21 has an interior hole or opening 25, and at the lower end of this hole or opening 25, a portion of the metal is struck up or offset from the frame-member 21, to provide a pocket-portion 26 preferably having a rounded cam-like edge 27.

Secured to the frame-member 21, by a rivet 28 or other suitable means, is a resilient clasp-member 29, here shown in the form of a leaf-spring made of suitable spring-metal and preferably having its upper end 30 bent transversely toward the rear side 31 of the clasp and fitting between the lateral spaced-apart edges 32 and 33, and also engaging against the edge 34, the edges 32, 33 and 34 being bordering edges of a notch or recess 35 formed in the frame-member 21.

The lower end of the clasp-member 29 is preferably curled to form a cam-like lower end or grip-tongue 36. This lower end 36, when in the unclasped or open position illustrated in dotted lines in Fig. 2, stands spaced away from the cam-edge 27, thus permitting fabric 37 such, for example, as the upper portion of a stocking or sock, to be readily slid up between the parts 36 and 27, whereupon by pressing the portion 36 toward the cam-edge 27, the central portion of the resilient clasp-member 29 yields or springs sufficiently to permit the portion 36 to ride over 35 past the edge 27 and engage in the pocket-portion 26, to thus secure the fabric 37 securely in position without risk of tearing the same.

When it is desired to unclasp the clasp, it is merely necessary to push the clasp-member 29 toward the front of the clasp, either by pressing against the same at the intermediate portion 38, or by pushing against the end-portion 36, whereupon the latter moves to its dotted-line position and releases the fabric 37.

In the form of the invention illustrated in Fig. 4, the leaf-spring member 39 is provided with transverse bends or flutes 40 to increase the yieldability of the clasp-member 39. Instead of providing a pocket-portion such as 26 in Fig. 2, this can be omitted by merely having the gripping-edge 41 rounded to cam-like form and leaving it right in the plane of the frame-member 42. Otherwise, the action of the form of

the invention illustrated in Fig. 4 is similar to that shown in Figs. 1 to 3.

The novel principle of the present invention is embodied in a somewhat different form of construction in the modification of the invention shown in Figs. 5, 6, 7, and 8, wherein the frame-member 43 is formed of a single piece of spring-wire, which may have its ends welded together at 44. The wire frame-member 43 is provided with 10 oppositely-bent portions 45 and 46, which form a central hole or opening 47 for a purpose to be later described.

The portions 45 and 46 may be spaced from one another slightly at 48, if so desired. The 15 resilient clasp-member 50, in the form of a leaf-spring, is fastened to the frame-member 43 by means of a rivet 51.

The clasp-member 50 may have its extreme end provided with a bend 52 to engage against 20 the bottom 53 and sides 54 and 55 of a recess 56, to firmly position the clasp-member 50 against lateral movement. The front end 57 of the rivet is preferably of large diameter, and is pressed or hammered down over the adjoining parts 45, 46, etc., of the wire frame 43, to firmly secure the parts 45 and 46 against any spreading or opening action thereof.

The lower end of the clasp-member 50 is provided with curled or cam-portions 58 and 59 at 30 its opposite sides, so that when the clasp-member 50 is pressed from its unclasped position shown in dotted lines in Fig. 7, to its clasped position indicated in full lines in Figs. 5, 6, and 7, the cam-portions 58 and 59 ride over the rounded or cam-shaped wire-portions 60 and 61, to cause the latter to spread apart and permit the cam-portions 58 and 59 to move to the rear of the frame 43 to clasping position.

If desired, the clasp-member 50 may be provided with one or more longitudinal flutes or 40 ridges 62, to increase the flexibility of the clasp 50 and to increase the ease of the locking and unlocking action. Thus, in the form of the invention illustrated in Figs. 5, 6, 7, and 8, instead of 45 the locking action being along one edge, as in Figs. 1 to 4, the locking action against fabric occurs at the two locations, by means of the cam, grip-tongue portions 58 and 59 of the clasp-member 50.

In the form of the invention illustrated in Figs. 9, 10, 11, and 12, the locking action is at one locking or gripping edge, as in Figs. 1 to 4, but in this modification of the invention, both the frame-member 63 and the clasp-member 64 are made of 50 spring wire. The frame-member 63 in all its essentials is similar to the wire frame-member 43 of Fig. 8 except that the opening 65 is of different form. The clasp-member 64 has opposite portions 66 and 67, shaped to form a central hole or opening 68, and may have their upper ends welded or otherwise joined at 69. If desired, the shoulder-portions 70 and 71 may be slightly spaced apart from each other. The parts 63 and 64 are joined together by means of a rivet 72 having large front and rear head-portions 73 and 74, so that the head-portions can be pressed or hammered down around and beyond the adjoining arm-portions of the members 63 and 64, as more clearly shown in Fig. 10, to firmly anchor 70 these two parts against relative side rotational movement.

In the form of the invention illustrated in Fig. 13, the frame-member 75 and clasp-member 76 are made of spring wire in substantially the same manner as in the case of the form of invention

shown in Figs. 9, 10, 11, and 12, but the form of the invention shown in Fig. 13 has the clasp-member 76 formed to have double opposite-side clasping action similar to that shown in Fig. 5, instead of the single-end clasping action of Fig. 9. 5 Otherwise, the mode of operation of the form of the invention shown in Fig. 13 is similar to that of Figs. 5, 6, and 7.

The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claims are intended to be embraced therein.

I claim:

1. A clasp comprising: a frame-member having an opening and a gripping-edge forming part 20 of the border of said opening; a resilient metal or equivalent clasp-member rigidly secured to the frame-member and having a grip-tongue adjacent said gripping-edge and at one side of said frame-member when in unclasped position, the extreme end of said grip-tongue being located substantially beyond said opening and beyond said gripping-edge when in unclasped position and said grip-tongue being adapted to resiliently engage against and yieldably resist being pushed 30 past said gripping-edge to gripping position adjacent said gripping-edge of said frame-member.

2. A clasp comprising: a frame-member having an opening and a gripping-edge forming part 35 of the border of said opening; a resilient metal or equivalent clasp-member rigidly secured to the frame-member and having a grip-tongue adjacent said gripping-edge and at one side of said frame-member when in unclasped position, the extreme end of said grip-tongue being located substantially beyond said opening and beyond said gripping-edge when in unclasped position and said grip-tongue being adapted to resiliently engage against and yieldably resist being pushed past said gripping-edge to gripping position adjacent said gripping-edge of said frame-member, said gripping-edge and said grip-tongue having cam action relative to one another to facilitate movement of said grip-tongue past said gripping-edge.

3. A clasp comprising: a generally-flat frame-member having an opening and a gripping-edge at the front side and offset from the general plane of the frame-member and forming part of the border of said opening; a resilient metal or equivalent clasp-member rigidly secured to the frame-member and having a grip-tongue adjacent said gripping-edge and at the front side of said gripping-edge when in unclasped position, the extreme end of said grip-tongue being located substantially beyond said opening and beyond said gripping-edge when in unclasped position and said grip-tongue being adapted to resiliently engage against and yieldably resist being pushed past said gripping-edge to gripping position adjacent the rear side of said gripping-edge with the grip-tongue end of said clasp-member located forward of the rear face of said frame-member.

4. A clasp comprising: a generally-flat frame-member having an opening and a pocket-portion provided with a gripping-edge at the front side and offset from the general plane of the frame-member and forming part of the border of said opening; a resilient metal or equivalent clasp-

member rigidly secured to the frame-member and having a grip-tongue adjacent said gripping-edge and at the front side of said gripping-edge when in unclasped position, the extreme end of said grip-tongue being located substantially beyond said opening and beyond said gripping-edge when in unclasped position and said grip-tongue being adapted to resiliently engage against and yieldably resist being pushed past said gripping-edge to gripping position adjacent the rear side of said gripping-edge with the grip-tongue end of said clasp-member located forward of the rear face of said frame-member.

5. A clasp comprising: a frame-member having an opening and a gripping-edge forming part

10 of the border of said opening; a resilient metal or equivalent clasp-member rigidly secured to the frame-member and having a grip-tongue adjacent said gripping-edge and at the front side of and spaced from said frame-member when in unclasped position, the extreme end of said grip-tongue being located substantially beyond said opening and beyond said gripping-edge when in unclasped position and said grip-tongue being adapted to resiliently engage against and yieldably resist being pushed past said gripping-edge to gripping position adjacent and in contact with said gripping-edge of said frame-member.

15
